Primary Examiner — Jennifer Rivard

(57) **CLAIM**

I claim the ornamental design for an electric nail file, as shown and described.

DESCRIPTION

FIG. 1 a front perspective view of the electric nail file.
FIG. 2 is a rear perspective view thereof;
FIG. 3 is a right side elevation view thereof, the left side view is a mirror image;
FIG. 4 is a top plan view thereof; and,
FIG. 5 is a bottom plan view thereof.

1 Claim, 5 Drawing Sheets Fig. 1

Fig. 2
